UNITED STATES PATENT OFFICE.

EDWARD G. SHORTT, OF CARTHAGE, NEW YORK, ASSIGNOR TO INTERNATIONAL AIR BRAKE COMPANY, OF JERSEY CITY, NEW JERSEY, A CORPORATION OF NEW JERSEY.

MECHANISM FOR CONTROLLING AIR-BRAKES.

No. 862,205.

Specification of Letters Patent.

Patented Aug. 6, 1907.

Application filed March 6, 1902. Serial No. 96,900.

To all whom it may concern:

Be it known that I, EDWARD G. SHORTT, a citizen of the United States of America, and a resident of Carthage, in the county of Jefferson and State of New York, have invented certain new and useful Improvements in Mechanism for Controlling Air-Brakes, of which the following is a specification.

This invention relates to an improvement in mechanism or means for controlling air brakes, by which it is meant that I have devised a novel and effective means for enabling the pressure in the auxiliary reservoir and train-pipe to be normally maintained at such a degree that there will always be plenty on hand for every purpose for which it may be needed; and for enabling the supply of pressure to the train-pipe to be constantly kept up while the engineer's valve is in the "on lap" position, with pump running.

With this invention a fixed and certain release of the brakes whenever required may be had immediately. Also there is always an abundant supply of air for repeated graduations on long grades, or when frequent service stops are necessary, as well as whatever fluid-pressure may be requisite in case of emergency. Constancy of high pressure in the train-pipe is maintained, notwithstanding the leaks to which the train-pipe is commonly subjected. These and manifold other advantages and benefits I am enabled to attain through the construction, combination and arrangement of parts substantially as will be herein-after more fully described and claimed; wherein a novel feature in the engineer's valve is availed of to permit an uninterrupted feed or supply of air from the main reservoir to the train-pipe when the engineer's valve is in the on lap position; and wherein is employed means for preventing the escape of braking pressure exhaust except when the pressure in the auxiliary-reservoir or train-pipe has risen above a predetermined amount, the pressure which is constantly being supplied and maintained in the train-pipe and auxiliary-reservoir closely approximating the degree of pressure at which the release of braking pressure is permitted, so that a release of the brakes may be quickly accomplished under any and all circumstances that may arise by simply raising the pressure in the train pipe a few pounds which will result in so conditioning the braking pressure release means as to allow the exit of the exhaust to atmosphere. And the invention also comprises many details and peculiarities of structure and combination for the more perfect attainment of the paramount objects in view.

In the accompanying drawing illustrating my invention, Figure 1 is a vertical section of my improved means for controlling air brakes, the pipe that leads from the triple valve to the diaphragm chamber being

shown as coupled to the exhaust port of the triple valve, and the outlet valve arranged in connection with the diaphragm chamber being represented as open. Fig. 2 is a sectional elevation of the same on a reduced scale, with certain of the essential parts of an air brake system shown in elevational outline, the outlet valve for the exhaust which is arranged in connection with the diaphragm chamber being shown as closed. Fig. 3 is a horizontal sectional plan view of the engineer's valve which forms a part of the present invention, 60 said valve having a special attachment thereto, by means of which a certain amount of pressure from the main reservoir is allowed to pass into the train-pipe when the engineer's valve is on lap. Fig. 3a is a bottom plan view of the rotary valve which occupies a 65 position on the top of the main body of the engineer's valve. Fig. 4 is a side elevation of the engineer's valve with my improved attachment shown in section on the line a a of Fig. 3. Fig. 5 is a vertical section of an engineer's valve and is intended to show parts 70 commonly enter into the construction of such a valve. Fig. 6 is a vertical section of the same at right angles to the section of Fig. 5, and is designed to indicate more particularly the pressure-retaining or excess-pressure valve which permits only a certain 75 amount of pressure to pass into the train-pipe. Fig. 7 is a detail side elevation of the valve-provided addition which I have made to the engineer's valve. Fig. 8 is an end view of the same. Fig. 9 is a top plan view. Fig. 10 illustrates a modification of my invention, in that it shows a pipe leading from the diaphragm-chamber to the train-pipe, or train-pipe space of the triple-valve, instead of to the auxiliary-reservoir as is the case with that form of the invention shown in Figs. 1 and 2. 80 85 90

Similar characters of reference designate corresponding parts throughout the different figures of the drawing.

One of the principal features of this invention is the provision of a passage-way or channel between the exhaust-port of the triple-valve and the auxiliary-reservoir, or between said exhaust-port and the train-pipe, or the train-pipe space in the triple-valve; in which passage or channel is situated an outlet valve for the discharge to the atmosphere of the air exhausting from the 95 brake-cylinder, the operation of which valve is controlled by the pressure in the auxiliary-reservoir or in the train-pipe, accordingly as the channel or passage is connected to the one or to the other, said outlet valve only opening to discharge the pressure released from the 100 cylinder to the atmosphere when the pressure in the auxiliary-reservoir or the train-pipe is equal to or above a certain predetermined figure, say 60 pounds. I shall now proceed to describe in detail the construction and arrangement of the parts composing the said connec- 105 110

tion between the triple-valve exhaust-port and the auxiliary-reservoir, or between the triple valve exhaust port and the train-pipe, and the discharge valve belonging to said connection.

5. 1 denotes a triple-valve, of any suitable or preferred type, having thereon the exhaust outlet or discharge nozzle 2, through which the interior exhaust port 3 delivers the brake-cylinder exhaust to the atmosphere under ordinary circumstances, although not in the 10 present arrangement. Screwed into the discharge nozzle 2 is a short connecting pipe 4, the other end of which is screwed into a tee pipe 5, attached to one end of which is a valve body 6 containing a cock 7, which can be used, when desired, to render my present improvement 15 inactive and permit the discharge of exhaust directly to the atmosphere by providing an exhaust-outlet at this point. On the other end of the tee pipe 5 is a vertical pipe 8 containing a spring 17 and a valve 16, which latter has a play relatively to its seat 16^a. Seat 16^a is 20 formed on the lower end of a hollow screw-threaded central projection 45 on the bottom of a casting 11, which constitutes the lower half of a chamber that contains a diaphragm, said projection 45 being screwed into the upper end of pipe 8. The upper half of the diaphragm 25 chamber consists of a casting 10. The two sections 10 and 11 are secured together by means of screws or bolts and between said sections is firmly held a flexible diaphragm 13 of suitable material. The upper section 10 is entered by a pipe 9 which leads to the auxiliary reservoir 20 in the form of the invention represented in Figs. 1 and 2, but which, in the form of the invention shown in Fig. 10, connects with the pipe 40 that leads to the train-pipe space of the triple valve, or to the train-pipe itself. Pipe 40 is provided with a cock 41 adapted for a 30 wrench or handle as shown in Fig. 10, this being for use when needed to disconnect the present improvement from the train-pipe. Valve 16 has a winged stem 45 that moves up and down in the hollow projection 45, the upper end of said stem entering the diaphragm chamber 40 beneath a block 14, which is rigidly secured to the diaphragm 13 near its center, said block 14 having feet 46 adapted to rest on the casting 11 when valve 16 is open and to be lifted a little above casting 11 when valve 16 is closed. It will be noted that the connection 45 between the valve stem 15 and the block 14 is a loose one, said parts being separate. The bottom 11 of the diaphragm chamber is provided with a series of holes or perforations 12, through which the pressure may exhaust into the atmosphere. Spring 17 carries at its 50 upper end a disk 18 having a downwardly extending projection 19 around which the upper end of the spring is coiled. The disk 18 preferably has its upper face dished, concaved or cup-shaped to conform more or less to the alignment of the valve 16, with which it is in contact. Spring 17 is tensioned between the disk 18 and a 55 rabbet or shoulder in the lower end of the pipe 8. Spring 17 normally has the function of holding the valve 16 against its seat 16^a, and in so doing the diaphragm 13 is flexed so as to be sprung at its center more or less above a horizontal plane. On the top of the diaphragm 13 is either reservoir pressure or train-line pressure, accordingly as the chamber is connected with reservoir or train-line, and the effect of such pressure is 60 constantly to tend to open the valve 16. The spring 17 is sufficiently strong, however, to hold the valve 16

closed, except when the pressure in the reservoir or the train-line against the diaphragm is above some predetermined figure, say sixty pounds, and when the pressure that tends to open valve 16 is more than sixty pounds, the spring 17 will be compressed, the valve 16 70 opened and a way of escape provided along the winged stem 15 through the lower half of the diaphragm chamber, and out into the atmosphere through holes 12, for such brake cylinder pressure as may exhaust through passages and pipes 3, 4, 5 and 8. When the pressure in the reservoir or the train-line is below sixty pounds, the valve 16 will be constantly kept closed, and therefore there can be no release of brake cylinder pressure at this time, and no release can be had at any time with this construction, except when the reservoir or train-line pressure is in excess of sixty pounds (or such other amount as may be determined upon), but in practice a pressure closely approximating this is always maintained by this invention. In order to release, it is necessary to raise the pressure in the train-pipe in the one 80 case, or in the train-pipe and the reservoir in the other case, to a degree which possesses valve-opening power for the discharge valve 16, but this involves only a slight change of pressure, and there is always enough stored to effect that slight change. For in order that pressure of releasing power may be readily secured, whenever needed for releasing purposes, I have invented a new and important attachment or addition to the engineer's valve whereby pressure may be supplied to the train-pipe and also to the auxiliary reservoir while the brakes are set, the parts of the triple valve in release position and the engineer's valve on lap, and this novel construction of engineer's valve, so indispensably necessary for use in the accomplishment of the best results in brake service, I will now 90 proceed to describe, the structural details being delineated in Figs. 3, 3^a, 4, 5, 6, 7, 8 and 9.

The engineer's valve now in common use—I refer especially to the familiar type of valve known as the Westinghouse—has the function of allowing compressed air to pass from the main reservoir to the train-line when the valve handle is in running or release position, but of not allowing any passage of air from the main reservoir to the train-line when the valve handle is on lap, for when the valve handle is on lap, all communication between the several parts is supposed to be cut off. Farther, this well known type of engineer's valve, which is now in use on railroads, is provided with a pressure retaining or excess pressure valve, which permits the pressure in the main reservoir to remain in excess of that in the train-line, because no matter how high a degree of pressure may be pumped into the main reservoir, only a limited amount, ordinarily seventy pounds, can pass this excess pressure valve into the train-line; and this excess-pressure valve is cut out 110 and rendered ineffective except when the engineer's valve is in running or release position. Hence, when the engineer's valve is on lap no air can pass into the train-line. Now, with my present improved engineer's valve, to which I have just briefly alluded, and which I shall now proceed to describe in detail, I provide a second pressure retaining valve which is designed to operate while the handle of the engineer's valve is on lap, but at no other time, being ineffective and cut out except when the on lap position has been 120

taken; and said second pressure-retaining valve permits air to pass from the main reservoir to the train-line at this time, but it is of such a character and is set with such a definite resisting power that pressure in excess 5 of a certain amount cannot pass, this amount being preferably not more than fifty pounds, or some figure thereabout, the pressure that is allowed to pass being less than the maximum allowed to pass through the ordinary retaining or excess pressure valve, and also less 10 than the releasing pressure required to control the valve device above described for the discharge of braking pressure, although the pressure which passes this valve on lap closely approximates the said release-controlling pressure. By permitting pressure to pass from the main 15 reservoir through the engineer's valve while it is in the on lap position, the pressure in the train-line is kept up to fifty pounds, or more, all the time, no matter how many service stops may have been made, or how numerous the drafts upon the train-pipe air and the air 20 stored in the auxiliary-reservoir, inasmuch as air is being constantly supplied to supplement these withdrawals, and if the pressure in the train-line and in the auxiliary reservoir can be kept up to fifty pounds, then when release is desired and the engineer's valve is 25 turned to release position, the provision of the extra ten pounds of pressure needed to lift the train-line or the reservoir pressure to releasing pressure will be secured with perfect ease and with scarcely any delay.

In order to facilitate a better understanding of the 30 novel construction and function of the improvements which I have applied to the engineer's valve, I will now first describe a common and well known example or type of Westinghouse engineer's valve, and then secondly will explain how I have added to its structure 35 and enhanced its usefulness and value. It is, of course, unnecessary to describe with great intricacy of detail the mechanism and operation of this common form of engineer's valve, for such a valve is one of the well-known essential elements of an air brake system, and is 40 familiar to all persons skilled in the art of train braking, and therefore my statement will be of a more or less general character without going into the minutiae of structure and arrangement.

Referring now to Figs. 3, 3^a, 4, 5 and 6, it will be observed 45 that I have illustrated one of the best known forms of Westinghouse engineer's valves in use at the present day. Proceeding now to briefly sketch its most salient and characteristic features in order that the nature and design of my improvement may be afterwards set forth with great perspicuity, 21 denotes the main valve body having a branch pipe 50 to which a pipe leading from the main reservoir may be coupled, a branch pipe 51 to which a connection with the train-pipe may be attached, a branch pipe 52 leading to the 55 equalizing reservoir, and a branch pipe 53 leading to a pump governor and gage. Inside of the body 21 is a seat 23 having therein a port 54 for receiving air from the main reservoir, and a passage 55 leading to the train-pipe connection 51. Above seat 23 is the rotary valve 24 having a handle 22 by which it is manipulated. Said valve 24 has the proper ports and passages to enable it to make the different connections between main reservoir, train-pipe and atmosphere. The valve handle 22 may be caused to occupy either 60 of five positions; first, release position; second, position

while running; third, on lap position where everything is blanked; fourth, position for making a service stop; fifth, position for making an emergency stop. When the valve handle 22 is in the position for releasing the 70 brake, air can enter the engineer's valve from the main reservoir and flow freely and directly to the train-pipe for releasing the brake and recharging the auxiliary-reservoir; when the handle 22 is in running position, communication directly between the main reservoir and train pipe ceases, but is kept up directly through 75 various ports and passages, and the feed valve whose function it is to limit the amount of pressure that enters the train-pipe, limit being ordinarily fixed at seventy pounds. When the handle is in the on lap position all ports in the rotary valve and seat are blanked. 80 When the handle is in the position for applying the brake and making a service stop an exhaust port is open to the atmosphere to discharge a few pounds of pressure. When the handle is in the position for applying the brake in the making of a sudden or emergency stop full communication is established between the train-pipe and the atmosphere. Within the valve body 21 is a piston 80 that controls the passage of air to the train-pipe and other parts at certain times, and under certain conditions, and which operates automatically in permitting and obstructing the flow. Alongside of the main valve casing 21 is a feed valve casing 32 containing a feed valve device 81; the precise construction of which it is unnecessary to give in detail, but the function of which valve is to allow only a certain degree of pressure to feed into the train-pipe while the engineer's valve is in running position, not over seventy pounds. This valve is variously denominated an excess-pressure valve, a pressure-retaining valve, or a feed valve having the characteristic of limiting the 90 quantity of the feed, and by this valve, when the handle is in running position, the pressure in the train-pipe is automatically cut off when it reaches seventy pounds regardless of any higher pressure that may be in the main reservoir. Among the various ports and passages in the main body 21 is a horizontal port 26 that carries air from the main reservoir to the feed valve casing 32, and its valve 81, and another horizontal port 95 25 that carries air from valve 81 and casing 32 to the train-pipe. The direction and relative position of 100 these ports 25 and 26 are clearly indicated in Fig. 3. Thus far in the present description of the engineer's valve referred to in this paragraph I have been dealing only with what is old and well known, and I lay no claim of originality thereto. Although I have had in 105 mind in what I have said and illustrated one particular Westinghouse type of engineer's valve, yet the characteristics specified belong quite generally to various different kinds. But I have made an extremely important addition to such a valve, an addition which is 110 unique and extremely useful in structure and function, and this I will now proceed to describe.

27 designates a thin plate or casting adapted to be inserted between the main valve body 21 and the feed valve body 32, and securely held in place by the same 115 bolts 56 57 that are ordinarily employed for attaching the valve body 32 to the valve body 21, except that they will be made a trifle longer. These bolts 56 pass through bolt holes 57 provided in plate 27 for the purpose, which holes 57 register with the bolt holes in the 120

body 21 and the body 32. Also plate 27 has therin two transverse inclined ports 58 and 59, the former registering with and forming a part of the reservoir passage 26, and the latter registering with and forming a part of the train-line passage 25, so that the introduction of the plate 27 into the organization of the engineer's valve does not disarrange the customary relation of the various parts of said valve or interfere with the main plan of its construction. It will moreover be evident that this attachment of mine can be applied to the engineer's valve with the greatest ease and facility and at only a trifling expense, for the cost of building the attachment is small and the connection is easily made by simply introducing the plate between the two valve bodies in the manner I have stated. Furthermore, the plate 27 is provided at one end with an enlargement or protuberance 60 serving as a valve body and containing a valve plug 29 having an operating handle 28, said plug 29 being of a conical form to correspond to the conical interior of the valve body 60, and said plug being hollow. Within the plug 29 is a valve 33 and its seat, said valve having a stem 61 that is enveloped by a spring 36 tensioned between the valve and a nut 34 that screws into and closes the lower end of the valve plug 29, said nut 25 having a sleeve like projection thereon which receives and accommodates the movement of the valve stem 61. Screwed into the bottom of the valve body 60 is a recessed plug 62 carrying a spring 35 that bears against the underside of the valve plug nut 34 and acts to force 30 the plug 29 upwardly into close contact with the conical interior of the valve body 60, in order that there may be a tight joint to prevent leakage. See Fig. 4. On one side of the valve 33 is a port 63 which communicates at times with a longitudinal port 31 in the plate 27, said 35 port 31 communicating in turn with a horizontal port 38 that leads transversely through the plate 27 and then for a short distance into the engineer's valve seat 23 where it communicates with a vertical port 37, which in turn registers with a port 39 in the rotary valve 24. 40 when the latter is in the on lap position, it being remembered that the air on top of the rotary valve 24 is main reservoir air, and, consequently, the ports 39, 37, 38, 31 and 63 provide a passage-way for main reservoir air to the valve 33. On the other side of the valve 33 is a 45 recess and port 64 which, when the port 63 is in communication with the passage 31, will be in communication with the longitudinal passage 30 running lengthwise in the plate 27 and connecting with the train pipe passage 25, see Figs. 3 and 4. The spring 36 belonging 50 to the valve 33 has a certain definite resisting power or strength, being set to permit only a certain degree of pressure to pass said valve from the main reservoir to the train-pipe, said degree being preferably fixed at fifty pounds, or thereabouts. Thus the function of this 55 valve, which may be called a feed-valve or pressure-retaining valve, is to allow only a limited amount of pressure, say fifty pounds, to pass from the main reservoir into the train pipe. But this valve never comes into operation except when the handle of the engineer's 60 valve is in the on lap position, and is in reality a feed valve for the on lap position of the engineer's valve handle. By the use of the handle 28, the plug 29 can be turned when desired so as to shut off all communication between the ports 30 and 31, or the ports 63 and 64, and 65 thus cut out this on lap feed valve and render it ineffect-

ive and idle. The movement of the handle 28 is limited by the stops 65 and 66 which define the position that it ought to assume when the valve is idle, or when it is active. Obviously from a consideration of the relative arrangement of the ports and passages which I have just described, and the position and function of the extra feed valve, it will be evident that when the engineer's valve handle 22 is placed in the on lap position, the port 39, by registering with port 37, will open the main reservoir to the train pipe through this feed valve and allow air to pass into the train pipe until the pressure in the latter amounts to fifty pounds, when the valve 33 will automatically shut off and prohibit any further influx of air to the train line.

I will now explain the operation.

80

Ordinarily as is well known when the engineer's valve handle is on lap everything is blanked, but with my improvements, when the handle is turned to the on lap position air still continues to feed to the train pipe. With the ordinary excess-pressure valve or feed valve 85 an air pressure of seventy pounds is allowed to pass to the train pipe when the engineer's valve is in running position, but the amount allowed to pass by my secondary or on lap feed valve is less than this, being only about fifty pounds. It will be noted, therefore, that in 90 the operation of my present system for controlling the action of air brakes there are three predetermined degrees of air pressure which bear a definite and fixed relation to each other. First, the release controlling pressure of the auxiliary reservoir or train-pipe amounting to say sixty pounds; second, the ordinary maximum charging pressure for train pipe and other parts of the system when the engineer's valve is in running position, which amounts to not over seventy pounds; and third, the on lap feed valve supply which amounts 100 to not over fifty pounds. It is essential that the on lap feed valve supply should be less than release controlling pressure, and that both of these should be less than the maximum supply afforded by the common form of engineer's valve, because of the paramount objects had 105 in view in this invention, as stated in the preamble to this specification, which are to maintain a plentiful supply of air in train pipe and reservoir for all the necessities of actual use, and to keep train pipe pressure nearly equal to but slightly below the release controlling 110 pressure, so that by a slight rise in the train pipe pressure release may be quickly had at any moment. The object of requiring a high pressure in order to control the release of the brakes is manifest when it is remembered that without this a constancy of high pressure 115 could not be maintained in the train pipe and auxiliary reservoir.

Having thus described my invention what I claim as new, and desire to secure by Letters Patent, is:—

1. In a fluid-pressure brake mechanism, the combination with an auxiliary-reservoir, train pipe, brake cylinder, and triple valve, of means for preventing at times and permitting at other times the escape of braking pressure exhaust, which means are controlled by the degree of pressure in a part of the system, and means for constantly supplying 120 and maintaining a pressure in the train-pipe and auxiliary-reservoir of a degree less but closely approximating the degree of pressure at which release of braking pressure is permitted, so that a release of the brakes may always be quickly effected by a small increase in the pressure in the 125 train pipe.

130

2. In a fluid-pressure brake mechanism, the combination with an auxiliary-reservoir, train pipe, brake cylinder and triple valve, of means for preventing escape of braking pressure exhaust except when the pressure in a part of the system has risen above a predetermined amount, and means for constantly supplying air to the train pipe and auxiliary-reservoir to cause the degree of pressure therein to be only slightly less than said predetermined amount, so that a release of the brakes may always be quickly effected by a small increase in train pipe pressure. 85
3. In a fluid-pressure brake mechanism, the combination with the essential elements of such a mechanism, of releasing means for the braking pressure operative only when the pressure in a part of the system exceeds a predetermined amount, and means for keeping the pressure in reservoir and train pipe so nearly up to said predetermined amount that the difference may be readily supplied from the excess in the main reservoir. 90
4. In a fluid-pressure brake mechanism, the combination with the essential elements of such a mechanism, of releasing means for the braking pressure operative only when the pressure in a part of the system exceeds a predetermined amount, said means consisting essentially of an outlet valve acted on by a spring, and a diaphragm constantly exposed to said auxiliary-reservoir or train pipe pressure, and means for keeping the pressure in reservoir and train-pipe so nearly up to said predetermined amount that the difference may be readily supplied from the excess in the main reservoir, said means consisting essentially of an engineer's valve that allows a limited feed to train pipe when handle is on lap. 100
5. In a fluid-pressure brake mechanism, the combination with the essential elements of such a mechanism, of releasing means for the braking pressure operative only when the pressure in a part of the system reaches a predetermined amount, and means for keeping the pressure in the reservoir and train-pipe so near said predetermined amount that the difference may be readily supplied from the excess in the main reservoir, said means consisting essentially of an engineer's valve that allows a limited feed to train pipe when handle is on lap, said limited feed closely approximating the said predetermined amount but being less than it. 110
6. In a fluid-pressure brake mechanism, the combination with the essential elements of such a mechanism, of releasing means for the braking pressure operative only when the pressure in a part of the system reaches a predetermined amount, and consisting essentially of an outlet valve having a diaphragm constantly exposed to said pressure, and means for keeping the pressure in reservoir and train-pipe nearly up to said predetermined amount, said means consisting essentially of an engineer's valve that allows a passage of air to train pipe while the handle is on lap, whereby quick release of the brakes by a small increase of train-pipe pressure may always be effected, and a plentiful supply of air for service or emergency actions always insured, and any loss through train-pipe leakage overcome. 120
7. In a fluid-pressure brake mechanism, the combination with the essential elements of such a mechanism, of means for preventing the release of braking pressure except at certain times, and means for constantly supplying air to the train pipe and auxiliary-reservoir until the pressure therein reaches a degree nearly equal to that required to effect release of braking pressure, the difference being readily supplied when needed from the excess in the main reservoir. 130
8. In a fluid-pressure brake mechanism, the combination with the essential elements of such a mechanism, of means for preventing the release of braking pressure except at certain times, and means for constantly supplying air to the train-pipe and auxiliary-reservoir to cause the degree of pressure therein to be less than but so nearly equal to said predetermined amount that the difference may be readily supplied from the main reservoir excess, whereby quick release of the brakes by a small increase of train pipe pressure may be effected, and whereby a plentiful supply of air for successive gradations as well as for emergency action may be always insured, and any loss through train pipe leakage overcome. 140
9. In a fluid-pressure brake mechanism, the combination with the essential elements of such a mechanism, of means for preventing the escape of braking pressure exhaust except at certain times, said means consisting essentially of a discharge valve controlling the exhaust and opening only by the action of said predetermined amount of train-pipe or reservoir pressure, and means for constantly supplying air to the train pipe and auxiliary reservoir to cause the degree of pressure therein to be less than but so nearly equal to said predetermined amount that the difference may be readily supplied from the main reservoir excess. 150
10. In a fluid-pressure brake mechanism, the combination with the essential elements of such a mechanism, of a passage-way leading from the brake cylinder exhaust, a valve in said passage that opens a discharge to the atmosphere, a spring acting to normally close the valve, and a diaphragm constantly exposed on one side to auxiliary-reservoir pressure, and having the function of opening the valve, which function is only exercised when the said pressure is of a predetermined amount, and means for constantly supplying air to the train pipe and auxiliary-reservoir to cause the degree of pressure therein to be less than, but so nearly equal to said predetermined amount, that the difference may be readily supplied from the main reservoir excess. 160
11. In a fluid-pressure brake mechanism, the combination with the essential elements of such a mechanism, of a passage-way leading from the brake cylinder exhaust, said passage-way having a valve body and a diaphragm-containing chamber, a valve in said body that opens to discharge braking pressure to the atmosphere, said valve having a stem, a spring acting normally to close the valve, and a diaphragm in the chamber which is adapted to exert a pressure against the valve stem, the other side of said diaphragm being constantly exposed to pressure in a part of the system, and said diaphragm having the function of opening the valve only when the said pressure reaches a predetermined amount, and means for constantly supplying air to the train pipe and auxiliary reservoir to cause the degree of pressure therein to be less than, but so nearly equal to said predetermined amount that the difference may be readily supplied from the main reservoir excess. 170
12. In a fluid-pressure brake mechanism, the combination with the essential elements of such a mechanism, of means for preventing the escape of braking pressure exhaust except when the pressure in a part of the system is of a predetermined amount, said means comprising a passage-way leading from the triple valve exhaust, and a valve in said passage that opens to discharge braking pressure to the atmosphere, said opening only taking place when the valve is acted on by said predetermined amount of pressure, and means for constantly supplying air to the train-pipe and auxiliary-reservoir to cause the degree of pressure therein to be less than but so nearly equal to said predetermined amount that the difference may be readily supplied from the main reservoir excess. 180
13. In a fluid-pressure brake mechanism, the combination with the essential elements of such a mechanism, of means for preventing the escape of braking pressure exhaust except when the pressure in a part of the system is of a predetermined amount, said means consisting essentially of a passage-way leading from the triple-valve exhaust, a valve in said passage that opens to discharge braking pressure to the atmosphere, a diaphragm acting at times to open the valve, said diaphragm being constantly exposed on one side to pressure in a part of the system, and a yielding device for closing the valve, and means for constantly supplying air to the train-pipe and auxiliary-reservoir to cause the degree of pressure therein and against the diaphragm to be less than but so nearly equal to said predetermined amount that the difference may be readily supplied from the main reservoir excess. 190
14. In a fluid-pressure brake mechanism, the combination with the essential elements of such a mechanism, of means for preventing at times and permitting at other times the escape of braking pressure exhaust, which means are controlled by the degree of pressure in a part of the system, and consist of a discharge valve situated in a passage-way leading from the brake cylinder exhaust, and 200

- having a spring arranged to close and a diaphragm to open the valve, which diaphragm is constantly exposed on one side to the pressure in a part of the system and is moved only when said pressure is of a predetermined amount, and means for constantly supplying and maintaining a pressure in the train-pipe and auxiliary-reservoir closely approximating the degree of pressure at which release of braking pressure is permitted, whereby quick release of the brakes by a small increase of train-pipe pressure may always be effected, and a plentiful supply of air for service or emergency action always insured, and any loss through train-pipe leakage overcome. 35
15. In a fluid-pressure brake mechanism, the combination with the essential elements of such a mechanism, of means for preventing the escape of braking pressure exhaust except at certain times, and means for constantly supplying air to the train-pipe and auxiliary-reservoir to cause the degree of pressure therein to be less than but so nearly equal to said predetermined amount that the difference may be readily supplied from the main reservoir excess, said means including an engineer's valve having one feed valve that is idle when engineer's valve is on lap and is operative only when it is in running position, and having also a second feed valve that is operative only when engineer's valve is on lap, the pressure allowed to pass into train-pipe through the second valve being less than that allowed to pass through the first, and only slightly below and closely approximating the aforesaid predetermined amount of release-controlling pressure. 40
- 20 16. In a fluid-pressure brake mechanism, the combination with the essential elements of such a mechanism, of means for maintaining a constant supply of air in the train pipe and auxiliary-reservoir of a degree less than but so nearly to that required to effect the release of braking 45
- pressure that the difference may be readily supplied from the main-reservoir excess, said means comprising an engineer's valve having a main body, a feed valve body containing a valve that allows the maximum charging pressure to pass to train-pipe when the handle is in running position, and a plate interposed between the two valve bodies and having suitable ports and passages, and carrying a valve casing containing a feed valve that is operative only when the handle is in the on lap position, this latter valve allowing a less pressure of air to pass than is allowed to pass through the first feed valve. 50
- 25 17. In a fluid-pressure brake mechanism, the combination with the essential elements of such a mechanism, of means for maintaining a constant supply of air in the train-pipe and auxiliary-reservoir nearly equal to a predetermined amount required to effect release, said means consisting of an engineer's valve having a feed-valve that is idle when the valve handle is on lap and is operative when it is in running position, and a second feed valve carried by a plate interposed between the body of the first feed valve and the main body of the engineer's valve, said plate having suitable passages and ports that register with passages and ports in the adjoining parts all arranged so that when the second feed valve is properly turned to connect a reservoir passage with a train-pipe passage, and the main valve handle is on lap, a passage may be opened 55 from the main reservoir or train-pipe and permit feed to train-pipe through this second feed valve while the on lap position is kept. 60
